UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNORS TO VICKERS LIMITED, OF WESTMINSTER, LONDON, ENGLAND.

ELEVATING MECHANISM OF HEAVY GUNS.

1,274,518.

Specification of Letters Patent.

Patented Aug. 6, 1918.

Application filed May 13, 1915. Serial No. 27,961.

To all whom it may concern:

Be it known that we, Sir ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in or Relating to the Elevating Mechanism of Heavy Guns, of which the following is a specification.

This invention relates to elevating mechanism for heavy guns of the kind that are elevated and depressed by a hydraulic motor, such as a press, controlled by means of a valve adapted to be operated both by the elevating hand wheel or the like, and by a safety depression gear for preventing the gun from being depressed into a position such that if fired it would cause damage to any part of the ship within the training arc of the turret and, in certain circumstances, for automatically elevating the gun from the danger zone.

According to this invention the control valve is mechanically connected both to the elevating hand wheel or the like and to the safety depression gear so that a more efficient control is obtained than is the case when hydraulic rams and valves are interposed between the control valve and the elevating hand wheel and also between the said valve and the safety depression gear.

In order that the said invention may be clearly understood and readily carried into effect we will describe the same more fully with reference to the accompanying drawings, in which:—

Figure 1 is a side elevation showing in a more or less diagrammatic manner a constructional form of the invention, and

Fig. 2 is an enlarged view of a portion of Fig. 1.

A is the elevation press the ram of which is connected through a link a to the trunnion arm A' of the gun. B is the control valve of the press A and C is the elevating hand wheel for operating the said valve.

In the example shown there is arranged around the turret a stationary cam rail D having as is well understood a contour conforming to the fittings or the like on the

deck within the training arc of the turret. 55 The turret carries a vertically slidable member E (herein referred to as the roller bar) which lies in contact with the cam rail and is adapted to operate, preferably through a bell crank lever e and a push rod e' , upon 60 a floating lever E' which in turn is connected (for example by a link e^2) to a pivoted arm E^2 carried by a non-elevating portion of the mounting. This pivoted arm is adapted to be actuated when the gun is being depressed by a tappet a' carried by the trunnion arm or by any other suitable part moving with the gun. The said floating lever is pivotally carried by a sliding rod or bar E^3 (herein referred to as the plunger 70 block).

The stem of the control valve B is connected by a bell crank lever B' to a rotary spindle B^2 which is slidably connected to a shaft C' operated by the elevating hand wheel C. 75 The said spindle is screw threaded to carry a screw threaded sliding sleeve E^4 which is adapted to receive movement, through a bell crank lever e^3 for example, from the aforesaid plunger block E^3 . The said sleeve 80 is controlled by a spring e^4 which holds the bell crank lever e^3 in contact with the plunger block.

In the event of the control valve B being moved by the elevating hand wheel to depress the gun when such depression would bring the gun into a dangerous position as aforesaid, the tappet a' strikes the pivoted arm E^2 . The floating lever E' is thus moved about the end of its lower arm thereby 90 causing the plunger block E^3 to displace the sleeve E^4 against the resistance of its spring e^4 and move the control valve to its cut off position owing to the screw threaded connection between the sleeve and the spindle B^2 connected to the valve stem; depression of the gun into the danger position is thereby prevented. If the turret is then trained it may happen that the gun again reaches a dangerous position with regard to 95 parts of the ship in which event the roller bar E is moved onto a higher portion of the cam rail D and the upward displacement of the roller bar causes the floating lever E' to be rocked about the point of connection of its 100 upper arm with the aforesaid link e^2 and the valve B to be shifted to elevate the gun until it is no longer in a dangerous posi-

tion; after the roller bar has been moved by the training of the turret out of contact with the raised portion of the cam rail the control valve will, under the influence of 5 the aforesaid spring e^4 controlling the sleeve E^4 , resume the position originally given it by the elevating hand wheel C and will continue to be depressed until arrested at its depression limit.

10 What we claim and desire to secure by Letters Patent of the United States is:—
1. In the elevating mechanism of ordnance, the combination with a pressure fluid elevating motor, the control valve thereof, 15 and the actuating handle of said valve, of a reciprocatory member connected to said valve, mechanical means positively moving said member axially from said actuating handle and automatically operating safety 20 depression gear positively moving said member axially to stop the motor.

2. In the elevating mechanism of ordnance, the combination with a pressure fluid elevating motor, the control valve thereof, and the rotary actuating handle of said 25 valve, of a pivoted member connected to said valve, a screw threaded member connected to said pivoted member, a sliding member connected with said screw threaded member, a spring for controlling said sliding member, a rotary member connected to said rotary actuating handle, means for slidably connecting said rotary member to the screw threaded member and means for axially displacing said sliding member against 30 its spring to prevent dangerous depression of the gun.

In testimony whereof, we affix our signatures.

ARTHUR TREVOR DAWSON.
JAMES HORNE.
